WHEEL STABILIZER WEIGHT

Leland S. Hamer, 4170 Lakewood Drive,
Lakewood, Calif.

Filed June 14, 1960, Ser. No. 60,959

Term of patent 14 years

(Cl. D14—30)

FIG. 1 is a front elevational view of a wheel stabilizer weight, showing my new design;

FIG. 2 is a top plan view;

FIG. 3 is a rear elevational view;

FIG. 4 is a side elevational view;

FIG. 5 is a bottom view; and

FIG. 6 is a sectional view taken as indicated by line 6—6 on FIG. 1.

I claim:

The ornamental design for a wheel stabilizer weight, as shown.
